UNITED STATES PATENT OFFICE.

ULYSSES D. EDDY, OF RYE, NEW YORK.

DESIGN FOR A RACK FOR INKSTANDS, &c.

SPECIFICATION forming part of Design No. 30,359, dated March 21, 1899.

Application filed February 21, 1899. Serial No. 706,415. Term of patent 7 years.

To all whom it may concern:

Be it known that I, ULYSSES D. EDDY, a citizen of the United States, residing at Rye, in the county of Westchester, State of New York, have invented and produced a new and original Design for Racks for Inkstands, Pens, Clocks, and Similar Articles, of which the following is a specification, reference being had to the accompanying drawing, forming part thereof.

As shown in the drawing, which represents a perspective view of a rack, showing my new design, the leading or material feature of my design consists of a circular or ring-shaped body A, beneath which are arranged angular and curved arms or supports B B, extending downwardly from the rear part of the ring-shaped body, forwardly under the same, and upwardly at the front of said body. The arms or supports B respectively have a straight portion b, extending downwardly from the rear portion of the circular or ring-shaped body, an upwardly-curved portion b', extending from the straight portion b forwardly under the ring-shaped body and beyond the plane of the front of said body, a straight front portion b², extending from the front end of the curved portion b' upwardly and rearwardly to a point adjacent to the front portion of the ring-shaped body, and a portion b³, extending forwardly in curved contour from the top end of the portion b². At the ends of the front portions b² b³ are formed

eyes or loops e, as shown. The junction between the ring-shaped body and the rear portions b of the arms or supports, between the portions b and b', between the portions b' and b², and between the portions b² and b³ are curved, as shown at c. The straight rear portions b b of the arms are arranged at approximately right angles to the ring-shaped body and converge toward their upper ends, while the remaining parts of the arms or supports are arranged in approximately parallel relative position.

The various parts and members forming the design are shown as of rod shape, approximately cylindrical in cross-section, and having a twisted surface contour.

It is apparent that this design is not only applicable to inkstand and pen racks, but is also adapted for racks for clocks and other similar articles.

Having described my invention, what I claim as new, and desire to secure by Letters Patent, is—

The design for a rack for inkstands, pens, clocks, and similar articles, substantially as herein shown and described.

In witness whereof I have hereunto set my hand in presence of two witnesses.

ULYSSES D. EDDY.
